US0D1087831S

(12) **United States Design Patent** (10) **Patent No.:** **US D1,087,831 S**
(45) **Date of Patent:** **** Aug. 12, 2025**

(54) **ADJUSTABLE STRAPPING BUCKLE**

(71) Applicant: **Yu Sheng**, Jiande (CN)

(72) Inventor: **Yu Sheng**, Jiande (CN)

(**) Term: **15 Years**

(21) Appl. No.: **29/984,129**

(22) Filed: **Jan. 14, 2025**

(51) LOC (15) Cl. **02-07**

(52) U.S. Cl.

USPC **D11/214**; D11/200

(57) **CLAIM**

The ornamental design for an adjustable strapping buckle as shown and described.

DESCRIPTION

FIG. 1 is a perspective view of an adjustable strapping buckle showing the claimed design.

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

1 Claim, 8 Drawing Sheets
